UNITED STATES PATENT OFFICE.

JAMES DANIEL JOYCE, OF PHILADELPHIA, PENNSYLVANIA.

UNWINDING DEVICE.

Application filed January 7, 1926. Serial No. 79,741.

This invention relates to unwinding devices for regulating the delivery of yarn, thread, and the like from rotating spools or bobbins.

It is the prime object of my invention to control the rotation of the spool or bobbin in such a manner as to compensate for the shock of the starting of the winding operation and for the series of irregular variations in speed of feeding due to the traversing of the thread guide and due to the variations in diameter of the cone of yarn or thread being wound on the bobbin; and to prevent the spool from overrunning when the thread breaks or the tension thereon is relieved for any reason; so that fine or delicate materials can be unwound at high speeds without undue strain or breakage.

In accomplishing these results it is my purpose to employ a flexible compensating arm forming one end of a coiled spring rotatably and adjustably mounted on a suitable rod and having a portion of said coiled spring formed to provide a suspension for a flexible brake band adapted to contact with a brake drum on the spool holder.

Other objects of my invention will be found in the accompanying specification and claims and will be disclosed in the accompanying drawings in which:

Figure 1 is a perspective view of my device;

Figure 2 is a side elevation of my device with the movable parts shown also in dotted lines.

Referring with greater particularity to the drawings it will be seen that my device is comprised as follows:

A substantially U-shaped frame 1 having arms 4 and 5 is provided with a plate 2 having an aperture 3 for the reception of means to secure said frame in position on the winding machine in connection with which it is to be used. Recesses 6 and 7 in the arms 4 and 5 are adapted to receive and to provide bearings for the ends of spool holder 8. Extending upwardly from the juncture of the arm 4 with the main portion of the frame 1 is an arm 9 bored at 10 to provide for the reception of a rod 11 which is fixed therein.

Mounted on the rod 11 and spaced from the bore 10 by a collar 12 is a coiled spring 13 of flexible steel wire. One end of said spring is extended to form a compensator arm 14 bent adjacent its end to form a bear-

ing for a rotatable thread guide or pulley 15. The other end of the spring 13 is fitted into a collar 16 mounted on the rod 11 and adapted to be adjusted in its position 60 on said rod by means of a set screw 17. Intermediate of its ends the spring 13 has a portion thereof extending outwardly therefrom and then bent to form a loop 18 parallel to the rod 11. This loop extends over 65 to a position adjacent the arm 9 and above the spool holder 8. A brake band 19 of flexible material is secured at one end to the loop and at its other end has secured there- 70 to a weight 20.

A stop 21 fixed to the arm 9 is bent above and parallel to the rod 11 to provide a stop for the arm 14 in its upward motion. The spool holder 8 is provided with a brake drum 22 against which the band 19 is adapt- 75 ed to bear.

My device having been described in detail its operation will be seen to be as follows:

The collar 16 is first adjusted to tension 80 the spring to the proper degree for the type of thread being used.

It will be noted that, when the arm 14 is against the stop 21, a considerable portion 85 of the band 19 bears against the drum 22 and that since the loop end 18 extends out over the drum a strong braking force is applied to the drum. This braking force prevents any overrunning of the spool when 90 the draft on the thread is released as when the winding reaches the smaller end of the cone. When the winding reaches the larger end of the cone being wound, the amount of thread being wound will be greater and the draft on the thread will bend the compensator arm downwardly moving the loop downwardly to a proportionate amount and releasing the portion of the brake band from 95 contact with the drum thereby decreasing the braking effect thereof and preventing 100 the breakage of the thread under the sudden increase in draft.

I claim—

1. In combination, in an unwinding device, 105 a frame, a rotatable spool holder mounted in said frame and having a brake drum rotatable therewith, a compensator rod mounted in said frame, a coil spring mounted on and adjustably secured to said rod, one end of said coil spring terminating in a compensator arm and thread guide, a flexible brake band, a portion of said coil spring inter-

mediate of its ends being adapted to movably support said brake band in position to contact with said brake drum.

2. In combination, in an unwinding device, a frame, a rotatable spool holder mounted in said frame and having a brake drum rotatable therewith, a compensator rod mounted in said frame, a coil spring mounted on and adjustably secured to said rod, one end of said coil spring terminating in a compensator arm and thread guide, a flexible brake band, a portion of said coil spring intermediate of its ends being adapted to movably support said brake band in position to contact with said brake drum, the movement of said compensator arm being adapted to vary the degree of contact of said brake band with said brake drum.

3. In combination, in an unwinding device, a frame, a rotatable spool holder mounted in said frame and having a brake drum rotatable therewith, a compensator rod mounted in said frame, a coil spring mounted on and adjustably secured to said rod,

one end of said coil spring terminating in a compensator arm and thread guide, a flexible brake band, a portion of said coil spring intermediate of its ends being formed in a loop adapted to support said brake band in position to contact with said brake drum. 25

4. In combination, in an unwinding device, a frame, a rotatable spool holder mounted in said frame and having a brake drum rotatable therewith, a compensator rod mounted in said frame, a coil spring mounted on and adjustably secured to said rod, one end of said coil spring terminating in a compensator arm and thread guide, a flexible brake band, a portion of said coil spring intermediate of its ends being formed in a loop 30 40 adapted to support said brake band in position to contact with said brake drum, and a stop to limit the upward movement of said compensator arm.

In testimony whereof I affix my signature.

JAMES DANIEL JOYCE.
